UNITED STATES PATENT OFFICE.

GEORGE A. STEINER AND JOHN EVANS, JR., OF SALT LAKE CITY, UTAH.

BASIN AND BATH-TUB ATTACHMENT.

No. 854,184.

Specification of Letters Patent.

Patented May 21, 1907.

Application filed October 1, 1906. Serial No. 337,033.

To all whom it may concern:

Be it known that we, GEORGE A. STEINER and JOHN EVANS, Jr., citizens of the United States, residing at Salt Lake City, in the county of Salt Lake and State of Utah, have invented certain new and useful Improvements in Basin and Bath-Tub Attachments, of which the following is a specification.

Our improvement relates to means for holding soap, combs, brushes etc., conveniently for use in connection with wash-basins and bath-tubs. It is of a kind that employs a pulley and chain with a balance weight, to maintain the article held by it, in the desired position. The balance weights are vertically adjustable and are also attachable to each other, and to a standard, which serves as a guide to the weights in their movements.

The accompanying drawing illustrates the device, reference being made to the various parts of the invention by figures, similar figure denoting corresponding parts in the several views.

In the drawing Figure 1 is a general view of the device in side elevation. Fig. 2 is an elevation partly in section on line $x-x$ of Fig. 1.

The invention comprises a standard 1, preferably an iron bar, and having at its bottom, a rigid arm 2, which is attachable to the tub, or wash-basin fixtures by a yoke 3. The arm 2 is provided with oblong slots 4 and with round holes 5 for the legs of the yoke 3, which can pass through them in two different directions, at a right angle to each other, to better adapt the arm for attachment to either a vertical, or a horizontal fixture. Nuts 6, on the threaded ends of the yoke legs, enable the yoke to be tightly bound on the fixture.

The main balance weight 7, has a perforated ear 8 to which a chain 9 is attached. This chain passes over a grooved pulley 10, which has bearings on the upper part of the standard 1. The article to be held is attached to the depending end of chain 9, by any preferred means. The weights are nested, and through each one is a central vertical hole 19, through which extends the standard 1, upon which the weights freely move, and are vertically adjustable. The weight 7 maintains the lightest article in equilibrium, or slightly overbalances it, so that the article is drawn up out of the way, when not in use. When the chain is extended by drawing out the article held, the weight 7 rises, but is prevented

from striking the pulley, by a collar 11, which is adjustably set on the standard by a set screw 12.

A lateral hole 13 is provided in the top, or main weight 7, and a screw 14, is adapted to enter this hole until its end enters the recess or hole in the weight next below it, and so connects the two weights together. It is sometimes desirable to temporarily bind the main weight to the standard, in order to maintain the article carried on the chain at the same relative distance from the pulley, and so the screw 14 is made long enough to be screwed in until its point bears against the standard 1: and when an extra weight as 15, is attached to the main weight, the screw 14 passes through the hole 16, in said added weight.

Other additional weights may be provided as desired, each having a recess 17, to engage the point of a screw 18, of the weight next above it.

The lowest weight rests on a platform 20, on the lower part of the standard 1.

What we claim and desire to secure by Letters Patent, is

1. In an attachment for basins and bath-tubs a balancing weight on a standard, said weight surrounding said standard and having a chamber in its lower part and a lateral hole entering said chamber and a screw in said hole for the purpose specified.

2. In an attachment for basins and bath-tubs a standard, a weight vertically adjustable thereon, a collar on said standard to limit the ascent of said weight, and means to temporarily bind said weight to said standard, substantially as described.

3. An attachment to basins and bath-tubs comprising a standard, a weight thereon having a chamber in its lower part and a lateral screw hole, an additional weight whose upper part is adapted to occupy the chamber in the weight next above it and having a recess in said upper part, and a screw in the screw hole of the weight next above it to engage said recess for the purpose stated.

4. In a basin and bath-tub attachment, a standard, an arm on said standard having a set of cross openings therethrough consisting of a slot and a hole, a yoke having threaded legs adapted to enter said slot and hole and nuts on said legs to tighten up said yoke, as described.

5. In an attachment for basins and bath-tubs having a vertical supporting standard,

a fixed arm on the bottom of said standard having two sets of cross openings there-through at a right angle to each other, each set of said openings consisting of a slot and a 5 round hole, a yoke whose threaded legs are adapted to pass through said openings and nuts on said legs to tighten up said yoke, as herein set forth.

In testimony whereof I have signed my name to this specification in the presence of 10 two subscribing witnesses.

GEORGE A. STEINER.
JOHN EVANS, JR.
